(74) *Attorney, Agent, or Firm* — Mathieu Audet

(57) **CLAIM**

The ornamental design for a vibration absorber, as shown.

DESCRIPTION

FIG. 1 is an isometric view of an exemplary vibration damper in a closed version thereof;

FIG. 2 is a top plan view of the exemplary vibration damper in a closed version thereof;

FIG. 3 is a bottom plan view of the exemplary vibration damper in a closed version thereof;

FIG. 4 is a front elevational view of the exemplary vibration damper in a closed version thereof;

FIG. 5 is a back elevational view of the exemplary vibration damper in a closed version thereof;

FIG. 6 is a right side elevational view of the exemplary vibration damper in a closed version thereof;

FIG. 7 is a left side elevational view of the exemplary vibration damper in a closed version thereof;

FIG. 8 is an isometric view of the exemplary vibration damper in an open version thereof;

FIG. 9 is a top plan view of the exemplary vibration damper in an open version thereof;

FIG. 10 is a bottom plan view of the exemplary vibration damper in an open version thereof;

FIG. 11 is front elevational view of the exemplary vibration damper in an open version thereof;

FIG. 12 is back elevational view of the exemplary vibration damper in an open version thereof;

FIG. 13 is a right side elevational view of the exemplary vibration damper in an open version thereof; and,

FIG. 14 is a left side elevational view of the exemplary vibration damper in an open version thereof.

The broken lines in the drawings illustrate portions of the vibration absorber which form no part of the claimed design.
